TAPE DISPENSER

John F. Cullen, Old Bridge, N. J., assignor to Permacel-Lepage's Inc., a corporation of New Jersey

Application November 26, 1957, Serial No. 48,669

Term of patent 14 years

(Cl. D74—1)

Fig. 1 is a side perspective view of a tape dispenser, showing my new design;

Fig. 2 is a top plan view thereof; and

Fig. 3 is an end elevational view thereof looking from the right end of Fig. 1.

The broken line showings of the supporting bracket in Fig. 1 and the rollers in Fig. 2 are for illustrative purposes only.

I claim:

The ornamental design for a tape dispenser, substantially as shown and described.
